UNITED STATES PATENT OFFICE

2,551,260

DRAWBENCH CARRIAGE

Glenn W. Garwig, Youngstown, Ohio, assignor to
 The Aetna-Standard Engineering Company,
 Youngstown, Ohio, a corporation of Ohio

Application December 2, 1946, Serial No. 713,439

2 Claims. (Cl. 205—24)

1

This invention relates to draw benches of the type used in the manufacture of tubes, bars, rods, etc., and more particularly to an improved draw bench carriage and gripper mechanism.

In the manufacture of drawn tubes (it being understood that where the term "tube" is used herein it is intended to include bars, rods, and the like) it is customary to provide an elongated draw bench having at one end a die stand which supports the die or dies through which the tubes being handled are drawn. A carriage is mounted on the draw bench bed or trackway and is movable by suitable means along the trackway toward and away from the die stand. In operation the ends of the tubes being drawn are pushed through the dies and the projecting ends gripped by jaws mounted on the carriage so that, when the carriage is moved away from the die stand, the tubes will be drawn through the die and the desired reduction imparted thereto.

In my copending United States Patent Application Serial No. 599,185, filed June 13, 1945, and now Patent No. 2,536,637, granted Jan. 2, 1951, I have described and claimed an improved draw bench arrangement having a self-propelled carriage which is driven along the trackway by pinion gears mounted on the carriage and engaging racks which extend lengthwise of the bed or trackway. Prior to the development of the apparatus of my said copending United States patent application it was customary and conventional to provide a heavy chain, having its upper reach movable away from the die stand, and adapted to be engaged by a hook mounted on the carriage. Independent cable means were usually employed with this type of apparatus to return the carriage to the die stand.

The present invention relates to an improved carriage and a gripper head which is particularly adapted for use with the self-propelled type of draw bench carriage disclosed in my above noted copending patent application but which, as will be understood by those skilled in the art, may also advantageously be used with the old style chain and cable operated draw bench carriage.

In the operation of draw benches of the type to which this invention pertains the carriage is returned to a position adjacent the die stand after each drawing operation. In the usual draw bench arrangement the return stroke of the carriage involves wasted time as no drawing is being done during this operation. Accordingly the carriage is returned as rapidly as possible and means are provided which are intended to stop the draw bench carriage when the gripper head is adja-

2

cent to or just engaging the die stand. However in actual operation it is found that the gripper head end of the carriage frequently engages the die stand with considerable impact. As the carriages are quite heavy and have considerable momentum, the sudden stopping upon striking the die stand places a substantial shock load upon the carriage structure. This is undesirable in any type of draw bench carriage arrangement but particularly so in the self-propelled type of carriage described and claimed in my above mentioned patent application in which the drive motor is mounted on the carriage with its shaft in horizontal position. This motor must be quite large to furnish sufficient power for the drawing operations and accordingly must have a relatively heavy armature, shaft, etc. The shock load imposed upon the motor bearings, and the bearings of the other parts of the carriage drive mechanism, due to impact of the carriage with the die stand may at times be severe and accordingly may cause damage to the thrust bearings of the motor shaft and associated parts.

It is therefore an object of my present invention to provide means for absorbing the impact load or shock which occurs when the gripper head end of a draw bench carriage strikes the die stand.

Other objects of my invention include: the provision of a unitary gripper head assembly which is resiliently mounted on a draw bench carriage whereby limited shock absorbing movement of the gripper head relative to the main frame of the carriage is permitted upon impact of the gripper head with the die stand; the provision of an improved gripper head construction for draw bench carriages which in addition to its usual stock gripping functions also serves as a shock absorber or resilient bumper for the draw bench carriage without in any way interfering with the effective operation of the gripper head in firmly and positively gripping the ends of the tubes as they extend through the die or dies in the die stand; the provision of a shock absorbing gripper head for draw bench carriages which is adapted to be used with either the old style hook, chain, and cable operated carriages or with the self-propelled motor driven carriages of the type shown in my previously referred to copending United States patent application, and which is also adapted to be used with carriages having gripper heads at each end for use with double acting draw benches in which die stands are provided at both ends of the bench and a drawing operation takes place

during each movement of the carriage along the bench; and, the provision of a rugged, simple, fully automatic shock absorbing gripper head for draw bench carriages which will stand up under severe usage and which requires a minimum of care and maintenance in use.

The above and other objects of my invention will appear from the following description of a preferred form thereof reference being had to the accompanying drawings in which:

Figure 1 is a plan view of a self-propelled draw bench carriage incorporating my improved gripper head, portions of the supporting trackways being shown together with a portion of the die stand, the carriage being illustrated in position 15 with the gripper head engaging the die stand and the resilient support for the gripper head being shown in cross-section.

Figure 2 is a side elevation of the apparatus shown in Figure 1, the gripper head mechanism 20 and ide stand being shown in vertical cross-section taken substantially on line 2—2 of Figure 1.

Figure 3 is an enlarged vertical cross-sectional view taken on line 3—3 of Figure 1.

Figure 4 is a horizontal cross-sectional view 25 taken on line 4—4 of Figure 3 but illustrating the gripper head assembly only.

Figure 5 is a vertical cross-sectional view of the apparatus shown in Figure 4, taken on line 5—5 of Figure 3.

Figure 6 is a front elevation, looking into the gripping jaws, of the gripper head shown in Figures 4 and 5, the jaws being in open or released position.

Figure 7 is a fragmentary side elevation of the 35 gripper head shown in Figures 4, 5, and 6.

As has previously been pointed out, my shock absorbing gripper head is particularly advantageous for use with the self-propelled draw bench carriage disclosed and claimed in my above 40 noted copending United States patent application and accordingly I have shown and will describe herein my improved gripper head as embodied in a draw bench carriage of this general type. Referring to Figures 1 and 2, the draw bench carriage comprises a main frame structure generally indicated at F. Supporting wheels 1, 2, 3, and 4 are mounted on the frame F and run on the spaced trackways 5 and 6. The inner faces of tracks 5 and 6 are provided with racks 7 and 8 which are engaged by drive pinions 9 and 10 respectively. These pinions are mounted on 45 vertical shafts, one of which is seen at 11 in Figure 2, the upper end of this shaft having a bearing in the housing 12 and the lower end carrying a suitable worm gear 13 which is enclosed in the housing 14. A corresponding worm gear 15 is mounted on the vertical shaft of pinion 9, and is enclosed in a housing 16. A worm 17 engages both of the worm gears 14 and 15 and is mounted on a shaft 18 which is supported in suitable bearings in the carriage frame F. Shaft 18 is coupled to the projecting shaft 19 of the reversible drive motor 20 which is also mounted on and carried by the frame F. Thus, when the motor 20 rotates in one direction the pinions 9 and 10, acting through the racks 7 and 8, will advance the carriage toward the die stand S and when the motor is rotated in the opposite direction the carriage will be moved away from the die stand to draw the tubes through the dies 21.

The forward end of the frame F is formed as a generally tubular support and housing 22 for the gripper head assembly G. This gripper head assembly includes a main body member 23 the rear

portion of which 24 (see Figure 5) is cylindrical and has a sliding fit within the inner bore of the tubular end portion 22 of the carriage frame F. Circumferentially spaced slots or key ways 25 are formed in the outer surface of the body 23 and keys or guide members 26 extend radially inwardly from the retaining ring 27 into the slots 26. A circumferentially extending shoulder 28 on the body 23 is adapted to engage the retaining ring 27 and limit the forward movement of the gripper head G relative to the carriage frame F, it being understood that the retaining ring 27 will be secured to the end of the tubular portion 22 of the frame F by suitable screws or the like. A shoulder 29 projects inwardly from the inner bearing surface of the tubular portion 22 of the frame F and, as is clearly seen in Figures 1 and 2, may act as a stop to prevent excessive inward movement of the gripper head G relative to the frame F.

In Figures 1 and 2 the gripper head G is shown in its forward or fully extended position with the shoulder 28 engaging the retaining ring 27. Sufficient clearance is provided between the inner end face 30 of the body 23 and the shoulder 29 so that under normal conditions of operation the body 23 will not strike the shoulder 29. From the above description it will be seen that the gripper head G is mounted for limited sliding movement in the frame F, being restricted in its forward movement by the retaining ring 27 and in its rearward movement by the shoulder 29 and being prevented from relative rotary movement in the supporting sleeve 22 by the keys 26 which extend into the key ways 25.

In order to provide a resilient backing for the 50 slideable gripper head G a group of four relatively heavy coil springs 31, 32, 33 and 34 are disposed symmetrically around the longitudinal center line of the gripper head G and are maintained under initial compression, one end of each spring abutting against the body 23 of the gripper head and the other end of each spring abutting against, and being disposed in shallow bores in, a transverse web 35 which is an integral part of the carriage frame F. The springs 31, 32, 33 and 34 extend into and are partially housed in the bores 31', 32', 33' and 34' in the gripper head body 23.

Thus the gripper head G is normally urged into its forward position as shown in Figures 1 and 2 by the springs 31, 32, 33 and 34. However, if and when the nose portions 36 and 37 of the body 23 strike the die stand S these springs will be compressed permitting the main carriage structure to advance toward the die stand under the resilient snubbing action of the springs thus cushioning the impact with the die stand and preventing the transmission of harmful shock loads to the carriage drive mechanism, etc.

The arrangement of the tube gripping jaws in the gripper head G may be of any suitable type but I have illustrated herein an assembly of jaws and jaw operating elements which are particularly well suited to be contained within the gripper head body 23 and to be entirely independent of the rest of the carriage structure. The nose portion of the body 23 is formed with a transversely extending opening having converging inner surfaces 38 and 39. The illustrated gripper head is provided with three pairs of gripping jaws, which are generally indicated at J, J' and J'' in Figure 6, and thus is adapted to grip and draw three tubes or bars simultaneously. 70 As the pairs of gripper jaws are substantially

alike in arrangement and mode of operation only the center set or pair, J' will be described in detail.

This center pair of jaws J' includes sliding jaw holders 40 and 41 supported for movement relative to the faces 38 and 39 of the body 23 by a bottom pair of guide plates 42-43 and a top pair of guide plates 44-45 which are supported parallel to but spaced from the faces 38 and 39 by brackets 46, 47, 48 and 49. Thus the jaw holders 40 and 41, which have outwardly extending flanges on their upper edges, are held in position to have guided sliding movement on the surfaces 38 and 39 respectively. Jaw teeth are formed on detachable members 50 which are clamped in position on the inner faces of the jaw holders 40 and 41 as is clearly seen in Figure 5.

When the jaw holders 40 and 41 are retracted as shown in Figure 5 the jaws are opened to receive the end of a tube or bar. When the jaw holders slide forward relative to the body 23 into the dot and dash line positions shown in Figure 5 they also move inwardly toward each other and cause the gripping action to take place. The three sets of sliding jaw holders are simultaneously operated by means of an equalizer bar 51 which extends across the transverse opening in the body 23 through slots 51' in the jaw holders (see Figures 4 and 5). Spring backed balls 52 are carried by the bar 51 on its front face and engage the forward sides of the slots 51' in the jaw holders (Figure 5 showing this engagement in jaw holders 40 and 41) to permit equalizing action between the individual sets of jaws in case the diameters of the three tubes being gripped are not exactly the same. The rear face of bar 51 engages the opposite sides of slots 51' and thus any movement of bar 51 is transmitted to each of the jaw holders.

A pair of rods 53 and 54 have threaded connection with the bar 51 at their forward ends and extend through and have bearings in the web 55 of the body 23. The rear ends of the rods 53 and 54 are secured to a rigid yoke member 56 (see Figures 4 and 5). This yoke extends upwardly and is connected by means of a pin 57 to an operating rod 58 which extends forwardly through the body 23 and is provided with a bearing at 59. A spring 60 surrounds the operating rod 58 and engages the body 23 at its forward end and the yoke 56 at its opposite end. This spring tends to move the yoke 56 to the right (Figures 2 and 5) and, as the yoke is connected to the rods 53 and 54 which are in turn connected to the equalizer bar 51, the spring 60 tends to hold the center pair of jaw holders, 40-41, together with the two end pairs of jaws J and J'', in retracted or open position as seen in Figure 5.

The outer or forward end of the operating rod 58 is tapered at 61 to facilitate its entry into a sleeve 62 mounted in the die stand S. On the side of rod 58 adjacent its outer end a notch 63 is formed which is adapted to be engaged by a spring backed plunger 64 mounted in the die stand and projecting a limited distance into the sleeve 62.

As is seen in Figure 1, the notch 63 and the plunger 64 are so shaped that when the carriage and the gripper head G approach the die stand S the operating rod 58 will enter the sleeve 62, 70 the plunger 64 will be initially pushed back by the end of rod 58 and then will snap into notch 63 as seen in Figure 1. As illustrated in Figure 2, the jaws of the gripper head are all held in retracted or open position by the spring 60. 75

When the carriage is started away from the die stand S on its drawing stroke the gripper head G moves positively with the carriage frame F because of the engagement of the shoulder 28 on 5 the body 23 with the retaining ring 27. However the engagement of the plunger 64 in the notch 63 is sufficiently strong, and the faces of the notch 63 are so shaped, that as the body 23 moves away from the die stand S the rod 58 and its associated 10 parts, including the pair of jaw holders 40 and 41 and their jaw members 50, remain stationary. This relative movement between the body 23 and the jaw holders 40 and 41 causes the jaw holders and jaws to be moved inwardly and to grip the 15 end of the tube which has previously been pushed through the die aperture 65. When the jaws 50 grip the stock further relative movement between the jaw holders 40-41 and the body 23 is prevented and the operating rod 58 will be pulled 20 loose from the bushing 62. As the carriage continues to move away from the die stand S the drawing resistance of the tubes will maintain the grip or bite of the jaws.

In order to provide means for manually operating the gripper jaws independently of the operating rod 58 I provide a cam finger 66 which is secured to a transverse shaft 67 rotatably supported in flanges 68 on the main carriage frame F (see Figure 3). An operating handle 69 is secured 25 to one end of the shaft 67 and if for any reason it is desired to move the jaws into gripping position independently of the action of the operating rod 58, the operator merely turns the shaft 67 in counter-clockwise direction as shown in Figure 2 causing the cam finger 66 to engage the yoke 56 and push it forward against the action of the spring 60. This operation will move the gripping jaws together in the manner previously described. As the shaft 67 is mounted in the carriage frame F it is necessary to provide slots 70 30 in the rear portion 24 of the body 23 to permit sliding movement of the gripper head assembly in the frame F.

From the above description it will be seen that 35 the automatic gripping action of the gripper head upon movement of the carriage away from the die stand is not in any way affected or interfered with by the shock absorbing relative movement of the gripper head body 23 and the frame F caused by impact with the die stand. If the nose of the gripper head strikes the die stand with considerable force the frame F will continue to move toward the die stand, compressing the shock absorbing springs 31, 32, 33 40 and 34. After compression the springs will expand and will tend to move the frame F away from the die stand. By providing a completely integral and self-contained gripper head unit which is entirely independent of the carriage frame F and is spring mounted thereon I have 45 provided an effective shock absorbing means for the draw bench carriage assembly while maintaining the advantages and mode of operation of the gripper head. By mounting another gripper head G on the opposite end of the carriage frame F in similar manner a double ended carriage may readily be constructed.

Although I have described the illustrated embodiment of my invention in considerable detail it will be understood by those skilled in the art that variations and modifications may be made in the form and arrangement of my apparatus without departing from the spirit of my invention. I do not therefore wish to be limited to the exact structure herein shown and described.

but claim as my invention all embodiments thereof of coming within the scope of the appended claims.

I claim:

1. In a draw bench carriage, a frame structure, a gripper head supported for movement relative to said frame structure and projecting from one end thereof, gripping jaws carried by said gripper head and movable relative thereto between gripping and retracted positions, and resilient shock absorbing means interposed between said gripper head and said carriage for resisting movement of said gripper head toward said frame structure. 10

2. In a draw bench carriage, a carriage frame structure having a hollow end portion, a gripper head disposed in said hollow end portion, guide means interposed between said gripper head and said frame structure for guiding said gripper head in movement relative to said frame structure substantially parallel to the direction 15 20

of travel of said carriage, stop means on said frame structure to limit movement of said gripper head relative thereto, spring means disposed in said hollow end portion between said frame structure and said gripper head and urging said gripper head away from said frame structure and cushioning movement between said gripper head and said frame, and gripping jaws carried by said gripper head.

GLENN W. GARWIG.
